(57) **CLAIM**

CPC G06F 3/048; G06F 3/0481; G06F 3/04812;

The ornamental design for a display screen or portion thereof with graphical user interface, as shown and described.

DESCRIPTION

G06F 3/04815; G06F 3/04817; G06F 3/0482; G06F 3/0483; G06F 3/0484; G06F 3/04842; G06F 3/04845; G06F 3/04847; G06F 3/0485; G06F 3/04855; G06F 3/0486; G06F 3/04886; G06Q 30/00; G06Q 30/02; G06Q 30/0237; G06Q 30/0238; G06Q 30/0239; H03J 1/00; H03J 1/0008; H03J 1/0016; H03J 1/0025; H04N 5/00; H04N 5/08; H04N 5/14; H04N 5/222; H04N 5/225; H04N 5/232; H04N 5/23222; H04N 5/23293; H04N 5/232933; H04N 5/232935; H04N 5/445; H04N 5/44504; H04N 5/45; H04N 21/00; H04N 21/234; H04N 21/431; H04N 21/4312; H04N 21/4314; H04N 21/4316; H04N 21/4532; H04N 21/4622;

The FIGURE is a front view of a display screen or portion thereof with graphical user interface according to our design. The outermost broken lines illustrate a display screen or portion thereof and form no part of the claimed design. The remaining broken lines illustrate portions of the graphical user interface that form no part of the claimed design.
